Primary Examiner — John A Voytek(74) *Attorney, Agent, or Firm* — Dunlap Bennett & Ludwig, PLLC(57) **CLAIM**

The ornamental design for an aircraft body, as shown and described.

DESCRIPTION

FIG. 1 is a front top perspective view of an aircraft body, showing my new design;

FIG. 2 is a front bottom perspective view thereof;

FIG. 3 is a front elevation view thereof;

FIG. 4 is a rear elevation view thereof;

FIG. 5 is a left-side elevation view thereof, with a right-side elevation view being a mirror image thereof;

FIG. 6 is a top plan view thereof; and,

FIG. 7 is a bottom plan view thereof.

The broken lines shown in the drawings depict portions of the article that form no part of the claimed design.

1 Claim, 4 Drawing Sheets(56)
